(57) **CLAIM**

The ornamental design for a multi-functional bracket, as shown and described.

DESCRIPTION

FIG. 1 is a perspective view of a multi-functional bracket showing my new design;

FIG. 2 is another perspective thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a bottom plan view thereof;

FIG. 8 is a top plan view thereof;

FIG. 9 is a perspective view of the multi-functional bracket where the multi-functional bracket is in a folded state;

FIG. 10 is an enlarged view of portion 10 shown in FIG. 1;

FIG. 11 is an enlarged view of portion 11 shown in FIG. 1;

FIG. 12 is an enlarged view of portion 12 shown in FIG. 2;

FIG. 13 is an enlarged view of portion 13 shown in FIG. 2; and,

FIG. 14 is an enlarged view of portion 14 shown in FIG. 7. The broken lines in the drawings depict portions of the multi-functional bracket that form no part of the claimed design.

1 Claim, 14 Drawing Sheets
